UNITED STATES PATENT OFFICE.

JOHN KELLY, OF CHICAGO, ILLINOIS.

DESIGN FOR A VALVE-CASING.

SPECIFICATION forming part of Design No. 32,922, dated July 10, 1900.

Application filed March 23, 1900. Serial No. 9,967. Term of patent 14 years.

To all whom it may concern:

Be it known that I, JOHN KELLY, a citizen of the United States, residing at Chicago, county of Cook, and State of Illinois, have invented and produced a new and original Design for Valve-Casings, of which the following is a specification, reference being had to the accompanying drawings.

Figure 1 is a view in perspective showing my valve-casing regarded from one end; Fig. 2, a similar view of the same regarded from the opposite end, and Fig. 3 an elevational view of the near end shown in Fig. 2.

The leading or essential feature of my design consists in a globe-shaped body or valve-chamber A, having the projections B and C extending from its opposite sides at right angles thereto, the larger projection D extending from one end at right angles to the direction of the extensions B and C, the cap or casing end D' for the part D, the parallel ears or lugs a flanking a central perforation

a' in the casing end D', and the smaller tubular projection E extending from the end of the casing opposite the extension D. As shown, the ears or lugs a have flat adjacent surfaces a² and are provided with perforations a³. The casing end D' is shown provided with peripherally - arranged recesses a⁴, extending at an angle to each other, the bottoms of said recesses or grooves forming chords of a circumference on the casing end D'.

Having described my invention, what I claim as new, and desire to secure by Letters Patent, is—

The design for a valve-casing, as herein shown and described.

In testimony whereof I have signed my name to this specification in the presence of two subscribing witnesses.

JOHN KELLY.
